UNITED STATES PATENT OFFICE.

HARRY W. STOVER, OF OAKLAND, AND BERTRAM M. COATES, OF PIEDMONT, CALIFORNIA.

DESIGN FOR AN AUTOMOBILE REAR-SIGHT DEVICE.

58,692.

Specification for Design.

Patented Aug. 9, 1921.

Application filed February 23, 1921. Serial No. 447,323. Term of patent 7 years.

To all whom it may concern:

Be it known that we, HARRY W. STOVER and BERTRAM M. COATES, citizens of the United States, residing at Oakland and Piedmont, in the county of Alameda and State of California, respectively, have invented a new, original, and ornamental Design for an Automobile Rear-Sight Device, of which the following is a specification, reference being had to the accompanying drawing, forming part thereof.

Figure 1 is a side elevation and Fig. 2 is a plan view of an automobile rear sight device, showing our new design.

We claim:

The ornamental design for an automobile rear sight device, as shown.

HARRY W. STOVER.
BERTRAM M. COATES.
